UNITED STATES PATENT OFFICE.

LOUIS CHARLES BELZ, OF PHILADELPHIA, PENNSYLVANIA.

DESIGN FOR A GAME-BOARD.

SPECIFICATION forming part of Design No. 29,482, dated October 11, 1898.

Application filed August 5, 1898. Serial No. 687,866. Term of patent 3½ years.

To all whom it may concern:

Be it known that I, LOUIS CHARLES BELZ, a citizen of the United States, residing in the city and county of Philadelphia, State of Pennsylvania, have invented and produced a new and original Design for a Game-Board, of which the following is a specification, reference being had to the accompanying drawings, forming part thereof.

- 10 The leading feature of my design for a game-board is a checkered field with representations of geographical localities thereon, a portion of said localities having inclosures around the same.
- 15 Figure 1 represents a plan view of a game-board embodying my design. Figure 2 represents a section on line $\alpha\alpha$, Fig. 1.

In the drawings, A designates the field of the game-board, the same having thereon the checkered lines B C, the representation of 20 geographical localities D, E, and F and inclosures G around said localities F.

Having thus described my invention, what I claim as new, and desire to secure by Letters Patent, is—

25 The design for a game-board substantially as shown and described.

LOUIS CHARLES BELZ.
